CLAIM

The ornamental design for a strap, as shown and described.

DESCRIPTION

FIG. 1 is a front view of a strap showing my new design; FIG. 2 is a rear view thereof; FIG. 3 is a left side view thereof; FIG. 4 is a right side view thereof; FIG. 5 is a top view thereof; FIG. 6 is a bottom view thereof; and, FIG. 7 is a perspective view thereof.

The broken lines depict portions of the strap that form no part of the claimed design.
